UNITED STATES PATENT OFFICE.

FRED H. DOERR, OF GRAND RAPIDS, MICHIGAN, ASSIGNOR TO DOERR MANUFACTURING COMPANY, OF GRAND RAPIDS, MICHIGAN, A CORPORATION OF MICHIGAN.

DESIGN FOR A COMBINATION MATCH AND CIGARETTE BOX AND ASH RECEPTACLE.

Application filed April 18, 1923. Serial No. 5,844. Term of patent 7 years.

To all whom it may concern:

Be it known that I, FRED H. DOERR, a citizen of the United States, residing at Grand Rapids, in the county of Kent and State of Michigan, have invented a new, original, and ornamental Design for Combination Match and Cigarette Box and Ash Receptacle, of which the following is a specification, reference being had to the accompanying drawing, forming part thereof.

The figure is a perspective view of a combination match and cigarette box and ash receptacle, showing my new design.

I claim:

The ornamental design for a combination match and cigarette box and ash receptacle, as shown.

FRED H. DOERR.
